CLAIM

The ornamental design for a three button control head, as
shown and described.

DESCRIPTION

FIG. 1 is a perspective view of a three button control head
showing our new design;

FIG. 2 is a front view thereof;

FIG. 3 is a top view thereof;

FIG. 4 is a first side view thereof;

FIG. 5 is a bottom view thereof;

FIG. 6 is a second side view thereof; and,

FIG. 7 is a rear view thereof.
